United States Patent Office

Des. 185,186
Patented May 19, 1959

185,186

HOSE NOZZLE

John D. Beinert, Babylon, N.Y., assignor to Melnor Industries, Inc., Brooklyn, N.Y., a corporation of New York

Application November 6, 1957, Serial No. 48,355

Term of patent 7 years

(Cl. D91—1)

Fig. 1 is a perspective view of the hose nozzle, showing my new design;

Fig. 2 is a front elevational view thereof;

Fig. 3 is a rear elevational view thereof; and
Fig. 4 is a top plan view thereof.

I claim:

The ornamental design for a hose nozzle, as shown.
